UNITED STATES PATENT OFFICE.

WILLIAM H. SAUVAGE, OF NEW YORK, N. Y., ASSIGNOR, BY MESNE ASSIGNMENTS,
TO GOULD COUPLER COMPANY, OF NEW YORK, N. Y.

SLACK ADJUSTER.

Application filed August 20, 1921. Serial No. 493,773.

To all whom it may concern:

Be it known that I, WILLIAM H. SAUVAGE, citizen of the United States, residing at New York, in the county of New York and State 5 of New York, have invented certain new and useful Improvements in Slack Adjusters, of which the following is a specification.

This invention relates to improvements in slack adjusters and more particularly to 10 automatic slack adjusters for use in connection with the brake rigging of railway cars. While the invention will hereinafter be described more particularly with reference to its application to railway truck brake rigging, it is, of course, to be understood that without material modification the slack adjuster may be interposed between the live 15 and dead levers of the foundation brake rigging between the trucks.

One of the objects of the present invention is to provide a simple and practical slack adjuster having relatively few parts which may be inexpensively manufactured and assembled.

A further object is to provide a slack 25 adjuster of the above type which is reliable and efficient in use and operation at all times and of durable construction.

A further object is to provide a slack 30 adjuster of the above type adapted to automatically take up and hold the excess travel of the brake rigging and at all times insure uniform piston travel or operation of the source of power applied.

Further objects will be in part obvious and in part hereinafter pointed out in connection with the accompanying sheets of drawings forming part of this disclosure, in the several views of which similar reference 40 characters indicate corresponding parts.

In the accompanying drawings, showing two of various possible modifications of the invention,—

Figure 1 is a plan view of a preferred 45 modification of the slack adjuster adapted to be interposed between the lower ends of the live and dead levers (not shown);

Figure 2 is a side elevation of the slack 50 adjuster shown in Figure 1;

Figure 3 is a right end view of the parts shown in Figure 2;

Figure 4 is a view showing the slack 55 adjuster applied to the lower end of a live lever;

Figure 5 is a sectional plan view of a slack 55 adjuster taken from the underside, showing a slight modification in the arrangement of parts; and

Figure 6 is a side elevational view of the form shown in Figure 5.

Referring to the drawings in detail and more particularly to Figure 1, 10 indicates the tubular part of a two-part telescopic push rod. The other part 11 is adapted to slide therein. These parts are provided at 60 their outer ends with fastening devices 12 and 13, which, by means of pins 14 or the like, are secured to the lower ends of the brake levers, the dead lever preferably being connected to the part 12 and the live lever to the part 13. This tubular member 10 is provided with an integrally formed housing 15, having a recessed portion 16, adapted to hold the ends of a plurality of holding devices, such as the dogs 17, these dogs being 65 of general rectangular shape provided with openings having case hardened edges through which the member 11 is adapted to pass. A spring 18 normally holds these dogs 70 in canted position, as clearly shown in Figure 1, whereby the edges 20 are adapted to bite into the rod 11 and prevent the relative inward movement thereof. Positioned 75 substantially parallel to this telescopic push rod is an adjusting rod 21 provided with an upturned end 22 having an eye 23 slotted so as to be adapted to engage a fulcrum pin or other fastening device 19 mounted part 80 way up the live lever, whereby, as the live lever is actuated beyond a certain predetermined amount, the fulcrum pin, which fits loosely in the eye to provide a certain amount of lost motion for brake shoe clearance, engages the end of the eye 85 23 and causes a relative movement of the adjusting rod 21 with respect to the telescopic push rod. This rod 21 passes through ears 24, preferably cast integrally with the housing 15 and between the ears 90 and on the rod 21 is a thimble 25 provided with a flange 26. There is also an auxiliary holding dog 27 lying substantially parallel to the dogs 17 and having an opening 95 through which the adjusting rod 21 passes. Interposed between the dog 27 and the thimble 25 is a coil spring 28 normally holding the dog in position to engage the adjusting rod.

It will also be noted that the tubular member 10 is provided with a second housing 30 within which the end of the adjusting rod 21 is adapted to move. Coiled about this adjusting rod and within the housing 30 is a coil spring 31 reacting between one of the ears 24 and a plate 32 held in place by a cotter pin 33 at the end of the rod 21. This spring normally holds the adjusting rod in such position as to hold one side of the slot or eye 23 in engagement with the fulcrum pin 19, passing therethrough, whereby the brake shoe clearance and lost motion is always insured. If the live lever 10 moves toward the right, pivoting on its fulcrum pin near the center, the brake shoes are forced against the wheels, and the pin 19 moved to the right side of the slot. Now as usually happens when cars are moving 20 and rumbling over rough tracks, a heavy vibration is caused which may tend to vibrate the adjusting rod still further to the right to the extent of the slot, so that on release of the brakes the usual brake shoe clearance off the wheels may be lost. For this reason, the cushion or compression spring 31, being under slight tension, prevents this rod 21 from moving except when positively moved as when excess wear of the 30 brake shoes or wheels takes place and the slack is to be taken up. In other words, this cushion spring is most important in preventing the occurrence of tight brakes. When the adjusting rod is tripped, releasing 35 at one and the same time the push rod, and the adjusting rod, this cushion spring tends to give prompt release of the slack adjuster proper, thereby permitting an easy replacement of the worn brake shoes.

40 The construction shown in Figures 5 and 6 is substantially the same in many respects. One of the more important points of difference, however, resides in the positioning of the dogs within the housing. In this 45 case, two dogs 40 are used, each being provided with an independently operable spring 41 and the dogs are spaced apart by means of a spacing pin 42 within the housing 15, being held in place by cotter pins 43. A 50 thimble 44 is positioned on the adjusting rod adjacent an auxiliary dog 45, and is held in the position shown in Figure 5 by means of a holding spring 46 reacting between the thimble and one ear 24 of the 55 housing. When the slack adjuster is tripped, for replacing worn brake shoes, the dog 45 moves to a position normal to the push rod 11 and the flanges 47 of the thimble 44 coact with the dogs 40 and move 60 them into releasing position. The adjusting rod 21 is provided with a coil spring 48 operating in substantially the same manner as the cushion spring 31, shown in Figure 1.

65 Both of the devices shown in the present

drawings operate in substantially the following manner: When the brakes are applied the upper end of the live lever 50, shown in Figure 6, moves toward the right, carrying the lower end of the live lever 70 relatively towards the left. This reacts through the two-part push rod to carry the lower end of the dead lever 51 towards the left, the upper end being firmly fixed in the usual manner. This tends to bring the 75 brake shoes into engagement with the wheels of the truck and apply the brakes. If at any time the travel of either lever exceeds that necessary to bring the brake shoes into operative braking relation with the peripheries of the wheels, due to wear of the parts or otherwise, then the pin 52, Figure 6, exceeds the lost motion provided for by the slot or eye 53 and causes a relative 80 outward movement of the adjusting rod 21 towards the right. This outward movement, of course, compresses the cushion spring 48. The adjusting rod is free to move in that direction by reason of its relation to the dog 45. When the brakes are released, the pin 90 52 drops back to the left hand of the slot or eye 53 carrying the brake shoes out of engagement with the wheels, whereupon the usual release springs on the brake rigging or top ends of the live levers continue to return said live lever into full release position, any excess travel of the adjusting rod slot forcing this rod to the right and still further compressing the cushion or compression spring 48, which tension remains 95 constant until dogs 40 are released for telescoping the push rod into the barrel. Spring 48 has no other function except to prevent this rod 21 from creeping through vibration to the right before the brakes are applied. The usual release spring, returning the live lever into full release position, pulls to the right the push rod 11, taking up all 100 excess travel of the slot 53 in the eye of the adjusting rod, thus compensating for any 105 excess travel of the live lever.

From the above, it will be seen that the present invention provides a simple and practical braking mechanism which is reliable and efficient in use and operation and well adapted to accomplish among others all of the objects and advantages herein set forth.

I claim:

1. In a slack adjuster, in combination, a two-part telescopic push rod, the outer ends of which are adapted to be connected with the live and dead levers respectively, an adjusting rod positioned substantially parallel thereto, a housing through which said adjusting rod passes, a plurality of dogs in said housing, some of said dogs co-coacting with the telescopic part of the push rod only, and another of said dogs coacting in release with both the push rod and the adjust- 120

- ing rod, and spring means normally holding said dogs co-acting with the telescoping push rod in canted position to the said last mentioned dog projecting outwardly from the housing whereby it may be moved to a position normal to the axis of the adjusting rod and simultaneously move the other dogs therewith, and a separate housing on the tubular part of said telescopic push rod enclosing part of said adjusting rod, and a cushion spring associated with said adjusting rod and positioned within said housing.
2. In an automatic slack adjuster, in combination with brake levers, a two-part telescopic push rod, a plurality of axially spaced holding means carried by one part and co-acting with the other, and a holding spring for each of said means.
- 20 3. In an automatic slack adjuster, in combination with brake levers, a two-part telescopic push rod, a plurality of dogs carried by one part and co-acting with the other, and a holding spring for each dog, said dogs being spaced apart.
- 25 4. In an automatic slack adjuster, in combination with brake levers, a two-part telescopic push rod comprising a tubular member and a rod-like member telescoping therewith, a plurality of axially spaced apart holding means carried by the tubular member and co-acting with the other part, and an adjusting rod associated with one of the levers for varying the effective length of said push rod.
- 30 5. In an automatic slack adjuster, in combination with brake levers, a telescopic push rod connecting said levers, an adjusting rod having a lost motion connection with one of the said levers, a spring coacting with one of
- the parts of said telescopic push rod, a return spring for the live lever, a plurality of holding dogs between the two parts of said telescopic push rod and a holding dog between one of said parts of the push rod and the adjusting rod.
- 35 6. In an automatic slack adjuster, in combination with brake levers, a telescopic push rod connecting said levers, an adjusting rod having a lost motion connection with one of said levers, a spring coacting with one of the parts of said telescopic push rod, a return spring for one of said levers, a plurality of holding dogs between the two parts of said telescopic push rod, a holding dog between one of said parts of the push rod and the adjusting rod, and independently operated springs, one for each of said dogs.
- 40 7. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said first mentioned dogs, said last mentioned dog projecting outwardly whereby it may be easily moved into a position at right angles to the axis of the push rod, thereby simultaneously moving the other dogs into a position at right angles thereto.
- 45 8. In an automatic slack adjuster, in combination with brake levers, a telescopic push rod connecting said levers, an adjusting rod having a lost motion connection with one of said levers, a spring coacting with one of the parts of said telescopic push rod, a return spring for one of said levers, a plurality of holding dogs between the two parts of said telescopic push rod, a holding dog between one of said parts of the push rod and the adjusting rod, and independently operated springs, one for each of said dogs.
- 50 9. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.
- 55 10. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.
- 60 11. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.
- 65 12. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.
- 70 13. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.
- 75 14. In an automatic slack adjuster, in combination with brake levers, a telescopic push rod connecting the lower ends of said levers, an adjusting rod having a lost motion connection with one of said lever fulcrums, a spring coacting with one of the parts of said telescopic push rod, a return spring for the live lever, a plurality of holding dogs between the two parts of said telescopic push rod, a holding dog between one of said parts of the push rod and the adjusting rod, and independently operated springs, one for each of said dogs.

In testimony whereof I affix my signature.

WILLIAM H. SAUVAGE.
